(57) CLAIM

The ornamental design for a golf ball, as shown and described.

DESCRIPTION

FIG. 1 is a front view of a golf ball showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a partial enlarged front view thereof.

Broken lines are included for the purpose of illustrating portions of the golf ball that form no part of the claimed design.
